(57) **CLAIM**

The ornamental design for a combined lighting and audio playing device as shown and described.

DESCRIPTION

FIG. 1 is a perspective view of a combined lighting and audio playing device showing my new design;
FIG. 2 is another perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a bottom plan view thereof;
FIG. 8 is an exploded view thereof; and,
FIG. 9 is another exploded view thereof.
The broken lines illustrate portions of the combined lighting and audio playing device that form no part of the claimed design.
